Ind., a corporation of Indiana

Original application December 13, 1935, Serial
No. 54,193. Divided and this application July
9, 1938, Serial No. 218,317

21 Claims. (Cl. 161—7)

This invention relates to improvements in timing mechanism.

This is a division of my copending application Serial No. 54,193, filed December 13, 1935, now 5 Patent No. 2,146,878, for Automatic sprinkler systems.

The objects of the invention are:

First, to provide a sprinkler system comprising a plurality of sprinkler units which may be timed 10 so that the units will cut in automatically and successively and will each be automatically and successively cut out after a predetermined period of operation.

Second, to provide a system of this type in 15 which the control means can be adjusted to time the various units and to vary the time of operation as desired.

Third, to provide a system of the type described 20 characterized by the reliability of the valve timing thereof.

Fourth, to provide a timing device of broad utility for initiating successive operations or steps in predetermined timed relation, the said device being fully adjustable to adapt the same to whatever 25 application it is desired.

Fifth, to provide timing mechanism for an automatic sprinkling system, which is simple in operation, being characterized by a minimum of moving parts.

30 Objects relating to details and economies of the invention will appear from the description to follow. The invention is defined and pointed out in the claims.

A preferred embodiment of the invention is 35 illustrated in the accompanying drawings, in which:

Fig. 1 is a diagrammatic view of a sprinkler system embodying the invention, a single sprinkler unit valve being illustrated, parts being broken away and sectioned for convenience in 40 illustration.

Fig. 2 is an enlarged plan view of the control timing panel with the cover plate removed, viewed along line 2—2 of Fig. 4.

45 Fig. 3 is a bottom plan view of the control timing panel.

Fig. 4 is an enlarged fragmentary view in section on line 4—4 of Fig. 2.

50 Fig. 5 is a fragmentary detail view of the control panel showing the valve timing dial and certain of the elements associated therewith.

Fig. 6 is a similar view illustrating the master or starting timing dial.

55 Fig. 7 is a sectional view along the line 7—7

of Fig. 1, illustrating one of the solenoid actuated controlling valves.

Fig. 8 is a fragmentary view in perspective of one of the valve timing cams and contact assemblies associated therewith.

Fig. 9 is a fragmentary perspective view of the master timing cams and contacts.

Fig. 10 is a wiring diagram for the system, various elements of the latter being shown 10 diagrammatically.

The automatic sprinkling system forming the subject matter of this invention comprises settable clock means for determining the time at which the valves in a sprinkling system may be opened to permit flow of water in the various 15 units. The control valves are actuated by solenoids, the timing of the current to each solenoid being regulated by the timing means aforesaid. Each valve governs the fluid pressure in a valve casing forming a part of the unit, so that by 20 the consecutive actuation of the successive solenoids, a plurality of units may be successively placed in or out of operation. A single sprinkler unit is illustrated and only one sprinkler of that unit. However, a series of the control valves 25 are indicated by dotted lines in Fig. 1.

Referring to the drawings, a supply pipe from a main header is indicated by the reference numeral 1. It will be understood that a main header supplies water to a plurality of unit supply pipes, the number thereof being dependent upon the number of sprinkler units included in the system. Pipe 1 is connected to a valve casing 2 to deliver water to the intake chamber 3 thereof. Connecting the intake chamber with 35 a discharge chamber 4 is a valve opening or port 5 having a beveled seat 6. The discharge or spray unit pipe 7 is connected to casing 2 at the chamber 4 and communicates in turn with sprinkling heads 7'. Coacting with the valve seat 6 is 40 a valve 8 connected to a pair of plungers 15, 16, adapted to actuate the valve. The plunger 16 is larger than the plunger 15 and the two plungers slide in portions of the valve casing 2 of a diameter corresponding to that of the plungers. The upper end of the casing is covered by a head in which is tapped a pipe fitting 30 connected to a pressure relief or exhaust pipe 31.

The foregoing valve structure constitutes a 50 differential pressure arrangement for governing the flow of fluid past the valve 5. This arrangement per se constitutes the subject matter of my copending application Serial No. 54,193 mentioned above to which reference may be had to 55

ascertain further structure and operation of the valve device.

The exhaust pressure relief pipe carries at its opposite end a fitting 32 which is tapped into the valve body 33 of a solenoid controlled valve actuating device 34. The valve body 33, as indicated in Fig. 7 is bored to provide passages 35, 36 and 37 communicating respectively with fitting 32, with a clean-out opening 38 having a closure plug 39, and with an exhaust elbow fitting 40 connected to a pipe 41 leading to a drain 42. A plunger valve 43 is arranged to slide in valve body 33 to govern the flow of water through passages 35, 36 and 37, depending upon the position of the valve. Valve 43 is actuated by a solenoid 44 mounted in a casing 45 above valve body 33 and secured thereto by screws 46.

The operation of the differential pressure valve device disclosed in Fig. 1 is controlled by the position of plunger valve 43. This valve governs the exhaust of fluid above the plunger 16 to in turn govern the pressure acting on the said plunger, or as pointed out in my copending application identified above.

It will be understood that each sprinkling unit will be composed of a set of sprinkling heads and control devices therefor including solenoid actuated plunger valve 43, casing 2 containing plungers 15 and 16, valve 8 and a supply pipe 1. I have shown the elements making up one unit only, for the purpose of simplicity of illustration. In Fig. 1, I have indicated by dotted lines a plurality of the control valve and sprinkler units.

The reference numeral 49 indicates a suitable conduit carrying therein a plurality of electrical conductors 50 which are appropriately connected to the solenoid terminals. At their opposite ends, conductors 50 are connected to terminals 51 marked "1", "2", "3", "4" on panel 52.

Adjacent the panel 52, I mount means for timing the successive energization of the solenoids 44 whereby to actuate control valves 43, comprising a master or starting timing synchronous motor 53 and a valve timing motor 54. These motors are identical, being a well known type of synchronous motor, geared by reduction gearing (not shown) to drive shafts 55 and 56 at the rate of one revolution in twenty-four hours and one revolution in four hours, respectively. Shafts 55 and 56 are journaled in plates 57 and 58 which likewise support mechanism to be hereinafter described for governing the flow of current in conductors 50.

Shaft 55 carries at the upper end thereof a pair of cams 59, 60 preferably of insulating material, which are adjustably secured together for rotation on the shaft. As illustrated in Figs. 2 and 9, cams 59 and 60 are similar in that a notch or drop 61 is formed in each of them, the notches being offset angularly around the shaft 55. Pivoted on a stem 62 carried by plate 57 are a pair of blocks 63 of insulating material, the upper block carrying a resilient conducting finger 64, while the lower block has a resilient conducting finger 65 mounted thereon. Fingers 64, 65 are resiliently pressed, against cams 59 and 60 respectively by coil springs 66, 67 secured at one end to clips 660 on blocks 63 and at the other end to a post 68 carried by plate 57. As clearly shown in Fig. 9, fingers 64 and 65 are provided with mutually facing or opposed coacting contacts 69 mounted on offsets 70 on said fingers. Mounted on each of blocks 63 at the side thereof opposite fingers 64 and 65 are rearwardly extending conductors 71, 72 having contacts 73 secured

thereto, the contacts 73 being in mutually facing or opposed coacting relation.

Finger 64 is electrically connected by a conductor 74 to a terminal 75 which, during the operation of the unit, is supplied with operating voltage, while finger 65 is connected to terminal 76 by a conductor 77. Cam contacting finger 64 is electrically connected to rearwardly extending conductor 71 and finger 65 is connected to conductor 72 by screws 78 extending through blocks 63. Accordingly, in the position shown in Figs. 2 and 9, in which finger 65 has passed notch 61 of cam 60, inasmuch as contacts 69 are together, current flows through conductor 74, finger 64, contacts 69, finger 65, conductor 71 15 and into a further conductor 79 which is connected to terminal 76. Current likewise flows at this time from fingers 64 and 65 through screws 78, conductors 71, 72, and through a conductor 80 connected to the latter to a terminal 81 of 20 motor 54.

Terminal 81 has likewise connected thereto a conductor 82 leading to a terminal 83 on an insulated cut-out block 84 which is pivotally mounted at 85 on the lower side of upper dial 25 panel 86 covering plates 51, 58 and the structure mounted on the plates. Block 84 has a further terminal 87 therein to which is connected conductor 88 leading to a switch 89. The switch is connected to one of the line terminals 90 by 30 a conductor 91. Conductor 88 is connected to conductor 74 at terminal 75 through switch 89.

Current is furnished to motor 54 from terminals 92, 93 of motor 53, which are connected by conductors 94, 95 respectively to line terminals 35 90 on panel 52. The circuit for motor 54 is as follows: Terminal 90 through conductor 96, terminal 97, motor 54, terminal 81, conductor 82, cut-out block 84, conductor 88, switch 89, conductor 91, and terminal 90. 40

Solenoid actuating current flows to finger 65 through conductor 74 connected at terminal 75 as hereinbefore described, terminal 75 being connected at switch 89 to the line voltage by a conductor not shown. 45

Upon the making of the circuit just described, motors 53 and 54 are actuated and solenoid energizing current in addition flows through conductor 77, terminal 76 and conductor 79 to the valve timing mechanism. 50

Mounted for rotation together with cams 59, 60 on shaft 55 at the upper end thereof, I provide a setting clip 98 having an upstanding nib 99 for coaction with notches 100 on the periphery of a calibrated master or starting dial 101, which is fixedly mounted on shaft 55. Clip 98 drives cams 59, 60 through dial 101 which is driven by shaft 55. When nib 99 is engaged in a notch 100, cams 59, 60 will be rotated by shaft 55. As illustrated in Figs. 1 and 6, clip 98 is bent so as to 60 extend above cover plate 86 for manual setting. An orienting pointer 102 facilitates setting of the clip. 65

Referring now to Figs. 2, 4 and 8, the valve timing mechanism is driven from shaft 56 which is journaled in a sleeve 103 mounted on plate 58. Calibrated valve timing dial 104 is fixed to the upper end of shaft 56 by a screw 105. Surrounding sleeve 103, I provide further telescoped or concentrically disposed sleeves 106, 107, 108, 109 70 each of which has rigidly mounted at the lower end thereof a cam 110 of insulating material and a setting clip 111 at the upper end thereof overlying plate 58. Clips 111 are provided with nibs or teeth 112 coacting with notches 113 in cali- 75

brated valve timing dial 104 and are marked "1", "2", "3", "4" for identification.

Disposed adjacent cams 110, I provide a circuit making and breaking assembly for each solenoid to be controlled. The structure thereof is shown in Fig. 8 and consists of a pair of blocks 115, 116, block 115 being rigidly clamped to a stem or post 117 mounted on plate 58, while block 116 is freely rotatable on the same post. Block 116 carries a resilient conducting finger 118 slideable on cam 110 during the rotation thereof. Contacts 119 are mounted on finger 118 and on a conductor 120 carried by fixed block 115. At the side thereof opposite finger 118 and conductor 120, blocks 115, 116 are provided with conducting members 121 carrying mutually facing contacts 122. The construction of the four block assemblies controlled by cams 110 is similar though the arrangement of the parts differs slightly, and the same reference numerals indicate corresponding parts. For the purpose of conveniently enabling contact fingers 118 to engage cams 110, I have reversed the mounting of blocks 115, 116 on stems 117, fixed block 115 being uppermost in two contact block assemblies, generally designated A, B respectively in Fig. 2 and lowermost in the other two assemblies designated C, D respectively in Fig. 2.

Conductor 120 on fixed block 115 is electrically connected to conducting member 121 on the opposite side thereof by a screw 123 extending through the block. In the case of the two contact assemblies A, B, the connecting wire 124 extends from conductor 121 on pivoted block 116 of one assembly A to conductor 120 on fixed block 115 of the succeeding assembly B, and the output conducting wires 125 extend from conductor fingers 118 to terminals 51 on panel 52.

The conducting fingers 118 are resiliently urged against cams 110 by means of springs 126 one end of each of which is attached to an anchoring lug 127 on block 116 and the other end to a post 128.

It will be noted that in the case of the two above noted contact block assemblies A, B the finger 118 is urged by its cam 110 in a direction to engage contacts 119, whereas in the other two assemblies, designated C, D in Fig. 2, the finger 118 is urged by the cam in the opposite direction, i. e., in a direction to separate contacts 119 and engage contacts 122. In order that the four assemblies shown shall operate in the same manner, I reverse the connection of the output and connecting leads 125, 124, respectively, for the assemblies C, D whereby the solenoid energizing or output circuit, rather than an assembly connecting circuit, is completed through contacts 122 when finger 118 drops off the cam shoulder. Thus, in the latter two cases, the output lead 125 is connected to the conductor 121 on pivoted block 116, while the connecting leads 124 for assemblies C, D are connected between the finger 118 on the pivoted block of assembly C and the conductor 120 on the fixed block of assembly D, completing a circuit therebetween when the contacts 119 are brought together, and the connector 124 between assemblies D and A extends from finger 118 on the former to conductor 120 on the latter.

The aforesaid reversal of connections is a matter of convenience only, the timing of the completion of the circuits in all cases being similar and depending on the passage of finger 118 past the shoulder of cam 110. The only difference is that in the two cases A, B the solenoid energizing circuit is controlled through contacts 119 while

the connecting circuit from one assembly to the next is controlled through contacts 122, and in the other two cases C, D the output circuit is controlled through contacts 122 while the assembly connecting current flows through contacts 119. In each case, the conductors 120, 121 on the fixed block are electrically connected while the finger 118 and contact 121 on the pivoted block are insulated from one another.

The input lead 79 for the timing contact assemblies is connected to conductor 120 on the fixed block 115 of the lowermost assembly as viewed in Fig. 2.

As seen in Figs. 2 and 8, I shape cams 110 to provide a shoulder 129, an intermediate step 130 and a second shoulder 131, to the end that upon release of finger 118 when shoulder 129 passes it, the previously existing contact between contacts 122 will be broken, yet contacts 119 will be restrained from coming into electrical connection for a brief period of time while finger 118 is in contact with step 130. This period is preferably about a minute and forty seconds, though it may be more or less depending on the extent of step 130.

Assuming that current is being supplied to the lowermost contact block assembly C illustrated in Fig. 2, flowing through lead 79 to the conductor 120 on fixed block 115 and the contacts 122 being engaged as shown, a circuit to the corresponding solenoid is completed as follows: Lead 79, conductor 120, screw 123, finger 121 on fixed block 115, contacts 122, finger 121 on pivoted block 116, output conducting wire 125, and terminal 51 to the solenoid. This circuit is maintained until finger 118 drops off cam shoulder 129 onto step 130, whereupon both pairs of contacts 119, 122 are broken for a short interval and no current flows. After the finger drops off step 130, contacts 119 are engaged and a connecting circuit through conductor 120, contacts 119, finger 118, and lead 124 is completed to the conductor 120 on the succeeding assembly D. This succeeding assembly controls the flow of electricity to a succeeding solenoid and cuts the same off after a predetermined interval in the same manner as described above. Following termination of the second energizing circuit, third and fourth circuits are successively made and broken in a similar manner, with the exception that the output or solenoid energizing current flows through contacts 119 and the assembly connecting circuit includes contacts 122.

By the above described mechanism, a unit is provided which will successively initiate flow through a number of hydraulic valves, which in turn control numerous sprinklers, and maintain it for a predetermined length of time, each hydraulic valve being automatically cut out after its period of operation has elapsed. Further, a short interval passes between operation of succeeding hydraulic valves. I have found it desirable to space cams 59 and 60 so that four hours elapse between the time when finger 65 on lower block 63 snaps over the notch 61 on cam 60 to bring contacts 69 and 73 together, thus energizing motor 54 and furnishing current through conductor 79 to the initial valve timing assembly, and the time when finger 64 on the upper block 63 snaps over notch 61 in cam 59 to permit the contacts 69 and 73 to separate and break the solenoid circuit.

In order to interrupt the current supplying motor 54, I utilize a cut-out block which is pivoted to the under side of cover plate 86 at 85. 75

Connected to terminal 83 thereon, which has been described, is a resilient bent conductor 132 provided at the free end thereof with a contact 133. Conductor 132 extends past a post 134 mounted between plates 58 and 86 and provided with an insulating jacket 135. A bent conductor 136 is connected to terminal 87 on block 84 and carries a contact 137 facing contact 133 and normally in engagement therewith. Block 84 is provided with an actuating arm in the form of a bent rod 138 extending in the path of a tappet 139 fixed to rotating valve timing dial 104 and depending therefrom. By the structure described, at a predetermined time tappet 139 impinges against rod 138 to rock block 84 about its axis and separate contact 137 from contact 133, inasmuch as contact 133 is restrained by insulated post 134. Accordingly, the circuit supplying motor 56 will be broken and its operation cease.

Switch 89 is placed in the circuit, to the end that the operation of the unit may be interrupted at will.

It will be apparent that a plurality of units such as I have described may be hooked together for control by the master timing motor, by changing the position of cams 59 and 60 to compensate for the addition of one or more units. Current may be led to such units from conductor 121 of the final pivoted block 116 of the present unit and through the duplication of elements and connections of the present assembly which need not be described.

As illustrated in Fig. 5, dial 104 is calibrated over one-half of its periphery in twelve major divisions indicating a two hour period. Notches 113 are placed at equal two and one-half minute spaces between these divisions and appropriately indicated by marks so that timing clips 111 may be set for inauguration of operation of their corresponding hydraulic valves at any chosen time. In the embodiment illustrated, the setting is made to operate successive solenoid valves for sixty-five, ten, five, and ten minutes. The difference between the nubs on the clips 111 marked "1" and "2" is the duration of time for the clip marked "2". The same applies to clip marked "3" and clip 111 marked "2", and the time of operation in this case would be five minutes, as each notch on dial 104 is for a duration of two and one-half minutes.

Fig. 6 indicates the mode of calibrating master or starting dial 101, the face thereof being divided into twenty-four hour periods with notches 100 formed therein at half hour periods. The portion of the dial between the six o'clock calibrations is shaded to indicate night and day periods. The setting in Fig. 6 indicates that at six o'clock in the evening finger 65 will fall off notch 61 in cam 60 to energize the unit for a four hour period.

It will be understood that dials 101 and 104 are to be correctly oriented with the respective pointers 102 prior to operation. Dial 101 should be set with respect to shaft 55 so that pointer 102 indicates the time of day on the dial at the time of setting. Dials 101 and 104 are calibrated and locked into position by screw 105.

In Fig. 10 I illustrate diagrammatically the more important of the instrumentalities as described above, together with a wiring diagram showing the circuits through which the clock motors and valve actuating solenoids are energized. Certain portions of the diagram have

been conventionalized or simplified for the sake of clarity.

Having reference to Fig. 10, it will be seen that master clock motor 53 is continually energized through the 110-volt supply wires 95, 94. Assuming switch 89 is closed and contact 137 is opened by the engagement of tappet 139 with rod 138 and likewise assuming contacts 69, 73 to be open, no current flows through synchronous clock motor 54 or through the timing system of circuit interrupters for the valve actuating solenoids 44. When finger 65 falls off cam 60 on the master motor shaft 55, making contacts at 69 and 73, a circuit (A) is completed through switch 89, wire 74, finger 64, contact 69, fingers 65, 72, wire 80, synchronous clock motor 54, and wire 96 to return wire 94, thus initially energizing and starting timing clock motor 54 and rotating shaft 56 on which the dial carrying tappet 139 and the timing cams 110 are mounted. This occurs at the beginning of the sprinkling period.

Simultaneously with the energization of motor 54, as described, tappet 139 passes rod 138, permitting contact 137 to be made and completing a circuit (B) through switch 89, contact 137, wire 82, synchronous motor 54, wire 96 to wire 94. Circuit (B) serves to keep motor 54 in operation even after contact 69 has been broken at the end of the sprinkling period and may be described as a sustaining circuit for clock motor 54.

When contacts 69, 73 are brought together by the passing of finger 65 off the shoulder of cam 60, a solenoid energizing circuit (C) is also completed through switch 89, wire 74, finger 64, contact 69, finger 65, wire 77, wire 79, first contact 119 (assuming it to be closed), wire 125, one of the solenoids 44, and the return wire 94. Accordingly, the first valve 43 is opened and the corresponding or first sprinkler brought into play. When the just mentioned contact 119 is initially broken by the dropping of finger 118 off the shoulder of its cam 110, circuit (C) is broken and the actuation of the first sprinkler 43 is interrupted. When the corresponding contact 122 is made, a circuit (C') is completed through switch 89, wire 74, finger 64, contact 69, finger 65, wire 77, wire 79, first contact 122, to the second contact 119 for the actuation of the second sprinkler, which second contact 119 is at that time closed. The second sprinkler is thus brought into play and operates for the desired period of time as determined by the setting of the clips 111, after which its operation is interrupted in like manner to that described with reference to the first sprinkler through the breaking of circuit (C''), which circuit is completed and interrupted in corresponding manner not necessary to further describe in detail.

Upon the breaking of the last circuit, the operation of the final sprinkler is terminated and at this time finger 64 passes off the shoulder of cam 59 breaking contacts 69, 73 and interrupting circuits (A) and (C). However, since sustaining circuit (B) is maintained, the operation of motor 54 continues until its dial setting is brought back to the starting point or zero, at which time tappet 139 engages finger 138 to break contact 137 and circuit (B), thus halting the operation of synchronous clock motor 54. The various timing parts are thus restored to initial position ready for a subsequent cycle on the next day when the dial 75

of the master clock 53 reaches the hour at which the sprinkling period is to start.

Obviously, the initiation and termination of the sprinkling period may be controlled as desired, likewise the period of operation of the individual sprinkler heads. Tappet 139 is so arranged as to pass out of engagement with finger 138 at the time when finger 65 passes off the shoulder of cam 60, whereby synchronous motor 54 and circuit (C) are simultaneously energized.

From the foregoing, it will be apparent that I have provided a sprinkler system which is positive in action and completely automatic. The timing means I have found to be reliable and its flexibility is apparent. Although particular reference has been made in the foregoing discussion to its application in a sprinkler system, those skilled in the art will appreciate that my timing unit has broad utility in any adaptation wherein a plurality of operations are to be definitely timed throughout a predetermined period and caused to repeat in like timed relation during a subsequent period. The parts of the unit are relatively simple and few in number.

I have illustrated and described my improvements in an embodiment which I consider very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. In an automatic sprinkler control of the type described, the combination of a plurality of solenoids adapted to be successively actuated, and timing means controlling the supply of current to said solenoids, comprising a synchronous motor, timing cams driven thereby, sets of timing contacts controlled by said cams, and means including connecting and output conductors respectively electrically connecting said sets together in succession as the cams are actuated by the motor, and electrically connecting each set to one of said solenoids, and return electrical connections from said solenoids whereby current is caused to flow successively through said solenoids for predetermined intervals in accordance with the relative positioning of the cams with reference to one another, said timing cams having delay portions for maintaining each set of contacts in an intermediate position wherein no current flows to the solenoid corresponding thereto nor to a succeeding set of contacts and its corresponding solenoid for a predetermined interval.

2. A timing device for a sprinkler system including a plurality of solenoid actuated governors adapted to be actuated in timed sequence with a predetermined short interval elapsing between the actuations of the solenoids of the governors, said device controlling the supply of current to the solenoids of said governors and comprising a synchronous timing motor, timing means driven thereby comprising a plurality of timing cams, and sets of timing contacts controlled by said timing cams, and means for manually adjusting the angular position of the individual timing cams, a master synchronous motor, a pair of cams driven thereby, master contacts having fingers engaging and controlled by said last named cams connected to said timing motor whereby actuation of said timing motor is controlled, and means for manually adjusting the position of said last named cams, means electric-

ally connecting said master and timing contacts, and conductors connecting said sets of timing contacts together and to said solenoids whereby current is caused to flow successively to said solenoids for predetermined intervals, said timing cams each being provided with a notched portion to permit the contacts controlled by a timing cam to be broken so that no current flows to the corresponding solenoid and to prevent flow of current to a succeeding set of contacts and solenoid for 10 said predetermined short interval.

3. A timing device for a system including a plurality of electrically-actuated governors adapted to be actuated in timed sequence with a predetermined short interval elapsing between the actuations of the governors, said device controlling the supply of current to the governors and comprising a synchronous timing motor, timing means driven thereby comprising a plurality of timing cams, sets of timing contacts controlled by said timing cams, and means for manually adjusting the angular position of the individual timing cams, a master synchronous motor, a cam driven thereby, a master contact controlled by said cam and connected to said timing motor whereby actuation of said timing motor is initiated, means electrically connecting said master and timing contacts, and conductors connecting said sets of timing contacts together and to said governors whereby current is caused to flow successively to said governors for predetermined intervals, said timing cams each being provided with a notched portion to permit the contacts controlled by a timing cam to be broken so that no current flows to the corresponding governor and to prevent flow of current to a succeeding set of contacts and governor for 25 said predetermined short interval.

4. A timing device for a system including a plurality of electrically-actuated governors adapted to be actuated in timed sequence with a predetermined short interval elapsing between the actuations of the governors, said device controlling the supply of current to the governors and comprising a synchronous timing motor, timing means driven thereby comprising a plurality of timing cams, a master synchronous motor, a cam driven thereby, a master contact controlled by said cam and connected to said timing motor whereby actuation of said timing motor is controlled, means electrically connecting said master and timing contacts, and conductors connecting said sets of timing contacts together and to said governors whereby current is caused to flow successively to said governors for predetermined intervals, said timing cams each being provided with a notched portion to permit the contacts controlled by a timing cam to be broken so that no current flows to the corresponding governor and to prevent flow of current to a succeeding set of contacts and governor for 30 said predetermined short interval.

5. A timing device for a system including electrically-actuated mechanisms adapted to be actuated in timed sequence with a predetermined short interval elapsing between the actuations of the mechanisms, said device controlling the supply of current to said mechanisms and comprising a synchronous timing motor, timing means driven thereby comprising a plurality of timing cams, output contacts controlled by said timing cams, and means for adjusting the relative angular position of the individual timing cams, a master synchronous motor, a master contact electrically connected to said timing motor and controlled by said master motor whereby actuation of said timing motor is initiated, and 35

means electrically connecting said master and certain of said output contacts, and means electrically connecting said output contacts together whereby current is caused to flow successively to said output contacts for predetermined intervals, said timing cams each being provided with a notched portion to permit the contacts controlled by a timing cam to be broken so that no current flows therefrom and to prevent flow of current to succeeding output contacts for said predetermined short interval.

6. A timing device for a system including electrically actuated mechanisms adapted to be actuated in timed sequence with a predetermined short interval elapsing between the actuations of the mechanisms, said device controlling the supply of current to said mechanisms and comprising a synchronous timing motor, timing means driven thereby comprising a plurality of timing cams, and output contacts controlled by said timing cams, a master synchronous motor, a master contact electrically connected to said timing motor and controlled by said master motor whereby actuation of said timing motor is controlled, and means electrically connecting said master and certain of said output contacts, and means electrically connecting said output contacts together whereby current is caused to flow successively to said output contacts for predetermined intervals, said timing cams each being provided with a notched portion to permit the contacts controlled by a timing cam to be broken so that no current flows therefrom and to prevent flow of current to succeeding output contacts for said predetermined short interval.

7. A timing device for a sprinkler system including a plurality of solenoid actuated governors adapted to be actuated in timed sequence, said device controlling the supply of current to the solenoids of said governors and comprising a synchronous timing motor, timing means driven thereby comprising a plurality of timing cams, and sets of timing contacts controlled by said timing cams, and means for manually adjusting the angular position of the individual timing cams, a master synchronous motor, a pair of cams driven thereby, master contacts having fingers engaging said cams and connected to said timing motor whereby actuation of said timing motor is controlled, and means for manually adjusting the position of said cams, means electrically connecting said master and timing contacts, and conductors connecting said sets of timing contacts together and to said solenoids whereby current is caused to flow successively to said solenoids for predetermined intervals.

8. A timing device for a system including a plurality of electrically-actuated governors adapted to be actuated in timed sequence, said device controlling the supply of current to the governors and comprising a synchronous timing motor, timing means driven thereby comprising a plurality of timing cams, sets of timing contacts controlled by said timing cams, and means for manually adjusting the angular position of the individual timing cams, a master synchronous motor, a cam driven thereby, a master contact controlled by said cam and connected to said timing motor whereby actuation of said timing motor is initiated, means electrically connecting said master and timing contacts, and conductors connecting said sets of timing contacts together and to said governors whereby current is caused to flow successively to said governors for predetermined intervals.

9. A timing device for a system including electrically-actuated mechanisms adapted to be actuated in timed sequence with a predetermined short interval elapsing between the actuations of the mechanisms, said device controlling the supply of current to said mechanisms and comprising a synchronous timing motor, timing means driven thereby comprising a plurality of timing cams, output contacts controlled by said timing cams, and means for adjusting the relative angular position of the individual timing cams, a master synchronous motor, a master contact electrically connected to said timing motor and controlled by said master motor whereby actuation of said timing motor is controlled, and means electrically connecting said master and certain of said timing contacts, and means electrically connecting said output contacts together whereby current is caused to flow successfully to said output contacts for predetermined intervals, said timing cams each having provision to permit the contacts controlled by a timing cam to be broken so that no current flows therefrom and to prevent flow of current to succeeding output contacts for said predetermined short interval.

10. A timing device for a system including electrically-actuated mechanisms adapted to be actuated in timed sequence with a predetermined short interval elapsing between the actuations of the mechanisms, said device controlling the supply of current to said mechanisms and comprising a synchronous timing motor, timing means driven thereby comprising a plurality of timing cams, and output contacts controlled by said timing cams, a master synchronous motor, a master contact electrically connected to said timing motor and controlled by said master motor whereby actuation of said timing motor is controlled, and means electrically connecting said master and certain of said timing contacts, and means electrically connecting said output contacts together whereby current is caused to flow successively to said output contacts for predetermined intervals, said timing cams each having provision to permit the contacts controlled by a timing cam to be broken so that no current flows therefrom and to prevent flow of current to succeeding output contacts for said predetermined short interval.

11. A timing device for a sprinkler system having a plurality of electrically-operated sprinkler units adapted to be actuated successively and for predetermined variable periods, said device comprising a plurality of contact members controlling the flow of energizing current to said units, certain of said contact members controlling the supply of current to other contact members, individual cam means for actuating each of said members to complete an energizing output circuit to a corresponding unit and to break said output circuit after a predetermined period and complete a connecting and energizing circuit to a succeeding contact member, said actuating cam means having provision for providing a short time lapse between the breaking and making of said last named circuit, adjustable driving means for the actuating means for said contact members permitting adjustment of the same relative to one another to control the period of energization of said respective units, comprising a motor-driven clock mechanism having a shaft on which said actuating means are mounted, and means for angularly adjusting said actuating cam means on the shaft, and cam controlled contact means for governing the initiation and termination of the

supply of current to the motor-driven clock mechanism and to said energizing circuits.

12. A timing device for a sprinkler system having a plurality of electrically-operated sprinkler units adapted to be actuated successively and for predetermined variable periods, said device comprising a plurality of contact members controlling the flow of energizing current to said units, certain of said contact members controlling the supply of current to other contact members, individual means for actuating each of said members to complete an energizing output circuit to a corresponding unit and to break said output circuit after a predetermined period and complete a connecting and energizing circuit to a succeeding contact member, adjustable driving means for the actuating means for said contact members permitting adjustment of the same relative to one another to control the period of energization of said respective units, comprising a motor-driven clock mechanism having a shaft on which said actuating means are mounted, and means for angularly adjusting said actuating means on the shaft, and cam controlled contact means for governing the initiation and termination of the supply of current to the motor-driven clock mechanism and to said energizing circuits.
13. A timing device for a sprinkler system having a plurality of electrically-operated sprinkler units adapted to be actuated successively and for predetermined variable periods, said device comprising a plurality of contact members controlling the flow of energizing current to said units, certain of said contact members controlling the supply of current to other contact members, individual means for actuating each of said members to complete an energizing output circuit to a corresponding unit and to break said output circuit after a predetermined period and complete a connecting and energizing circuit to a succeeding contact member, and adjustable driving means for the actuating means for said contact members permitting adjustment of the same relative to one another to control the period of energization of said respective units, comprising a motor-driven clock mechanism having a shaft on which said actuating means are mounted, and means for angularly adjusting said actuating means on the shaft.
14. A timing device for a system having a plurality of electrically-operated units adapted to be actuated successively and for predetermined variable periods, said device comprising a plurality of contact members controlling the flow of current to said units, certain of said contact members controlling the supply of current to other contact members, means for actuating said members to complete an output circuit to a corresponding unit and to break said output circuit after a predetermined period and complete a circuit to a succeeding contact member, said actuating means having provision for providing a short time lapse between the breaking and making of said last named circuit, and adjustable means for driving the actuating means for said contact members and to permit control of the period of energization of said respective units, comprising a motor-driven mechanism having a shaft on which said actuating means are mounted, and means for angularly adjusting said actuating means on the shaft to determine the time of initiation and duration of said periods.

15. A timing device for a system having a plurality of electrically-operated units adapted to be actuated successively and for predetermined

variable periods, said device comprising a plurality of contact members controlling the flow of current to said units, certain of said contact members controlling the supply of current to other contact members, means for actuating said members to complete an output circuit to a corresponding unit and to break said output circuit after a predetermined period and complete a circuit to a succeeding contact member, said actuating means having provision for providing a short time lapse between the breaking and making of said last named circuit, and adjustable means for driving the actuating means for said contact members and to permit control of the period of energization of said respective units.

16. A timing device for a system having a plurality of electrically-operated units adapted to be successively brought into operation for predetermined but variable periods, comprising a continuously-operative motor-driven master clock and an intermittently-operative motor-driven timing clock, means driven by said master clock for governing the initiation of a supply of energizing current to said timing clock, a plurality of contact members adapted to be successively supplied with output current for said units, means for actuating said contact members to complete successive output circuits to said units and thereafter to break said output circuits and complete circuits to succeeding contact members, said actuating means comprising a plurality of rotary cams actuated by said timing clock, each operatively engaging a contact member to actuate the same and having provision in the form of a notch in the periphery thereof to assure the lapse of a predetermined interval between the breaking and making of said last-named circuits, means for adjusting the relative angular position of said cams to vary the time of initiation and duration of said periods, means for adjusting said means driven by said master clock to govern the over-all period during which current is supplied to said contact members, and means for terminating the operation of said timing clock after a predetermined period of operation.

17. A timing device for a system having a plurality of electrically-operated units adapted to be successively brought into operation for predetermined but variable periods, comprising a continuously-operative motor-driven master clock and an intermittently-operative motor-driven timing clock, means driven by said master clock for governing the initiation of a supply of energizing current to said timing clock, a plurality of contact members adapted to be successively supplied with output current for said units, means for actuating said contact members to complete successive output circuits to said units and thereafter to break said output circuits and complete circuits to succeeding contact members, said actuating means comprising a plurality of cams, each operatively engaging a contact member to actuate the same, means for adjusting the relative position of said cams to vary the time of initiation and duration of said periods, and means for adjusting said means driven by said master clock to govern the over-all period during which current is supplied to said contact members.

18. A timing device for a system having a plurality of electrically-operated units adapted to be successively brought into operation for variable periods, comprising a master clock and a motor driven timing clock, a plurality of contact members adapted to be successively sup-

plied with output current for said units, individual means controlled by said timing clock for actuating said contact members to complete successive output circuits to said units and thereafter to break said output circuits and complete circuits to succeeding contact members, said actuating means being adjustable to determine the duration of said periods and having provision to assure the lapse of a predetermined interval between the breaking and making of said last named circuits, means driven by said master clock for governing the initiation of the supply of energizing current to said contact members, and means for adjusting said means driven by said master clock to govern the over-all period during which current is supplied to said contact members.

19. A timing device for a system having a plurality of electrically operated units adapted to be successively brought into operation for variable periods, comprising a master clock and a motor driven timing clock, a plurality of contact members adapted to be successively supplied with output current for said units, individual means controlled by said timing clock for actuating said contact members to complete successive output circuits to said units and thereafter to break said output circuits and complete circuits to succeeding contact members, said actuating means being adjustable to determine the duration of said periods, means driven by said master clock for governing the initiation of the supply of energizing current to said contact members, and means for adjusting said means driven by said

master clock to govern the over-all period during which current is supplied to said contact members.

20. A timing mechanism for controlling flow of current to a plurality of electrically actuated devices adapted to be energized in succession for predetermined periods comprising a master motor, a timing motor controlled by said master motor, contact means, means for actuating said contact means comprising a plurality of timing cams driven by said timing motor and operatively engaging said contact means, control means driven by said master motor, a circuit for energizing said contacts governed by said control means, and circuits for successively energizing said devices through said contact means, said last named circuits being controlled by said timing cams.

21. A timing mechanism for controlling flow of current to a plurality of electrically actuated devices adapted to be energized in succession for predetermined periods comprising a master motor, a timing motor controlled by said master motor, contact means, means for actuating said contact means comprising a plurality of timing cams driven by said timing motor operatively engaging said contact means, means to adjust the relative position of said cams, control means driven by said master motor, a circuit for energizing said contacts governed by said control means, and circuits for successively energizing said devices through said contact means, said last named circuits being controlled by said timing cams.

ALFRED C. ARBOGAST.
